Conrad Rauter.

Printer's Flourishes.

PATENTED
NOV 17 1868

CONRAD REUTER, OF CINCINNATI, OHIO.

Design No. 3,250, dated November 17, 1868.

DESIGN FOR PRINTERS' FLOURISHES.

The Schedule referred to in these Letters Patent and making part of the same.

To all whom it may concern:

Be it known that I, CONRAD REUTER, of Cincinnati, Hamilton county, Ohio, have invented a new Design for Printers' Flourishes; and I hereby declare that the said invention is correctly represented in the accompanying print, which forms a part of this specification.

I claim, and desire to secure by Letters Patent—

The design for printers' flourishes, substantially as herein represented and described.

In testimony of which invention, I hereunto set my hand.

Witnesses: CONRAD REUTER.
